A. LINDNER.

SWITCH LOCK.

APPLICATION FILED JAN. 24, 1917.

1,246,288.

Patented Nov. 13, 1917.

UNITED STATES PATENT OFFICE.

ARTHUR LINDNER, OF RICHMOND, INDIANA, ASSIGNOR TO THE RAM ENGINEERING COMPANY, OF COLUMBUS, OHIO, A CORPORATION OF OHIO.

SWITCH-LOCK.

1,246,288.

Specification of Letters Patent.

Patented Nov. 13, 1917.

Application filed January 24, 1917. Serial No. 144,280.

To all whom it may concern:

Be it known that I, ARTHUR LINDNER, a citizen of the United States, residing in the city of Richmond, in the county of Wayne 5 and State of Indiana, have invented a new and useful Switch-Lock, of which the following is a full, clear, and comprehensive specification and exposition, the same being such as will enable others to make and use 10 the same with absolute precision.

The object of my invention, broadly speaking, is to provide a switch-lock, by which the switch to which it is connected may be operated as desired by one having 15 the proper key for the particular lock to which it has been adapted, at the same time providing a switch-lock which will be simple in construction, efficient and convenient in operation, strong and durable in its several parts, light in weight, inconspicuous 20 and attractive in appearance, and which can be manufactured and sold at a comparatively low price.

More specifically stated, my object is to 25 provide a switch-lock so constructed and assembled that it cannot be picked or operated by experts or others not having an absolutely perfect key therefor, which key is not only adapted to unlock the lock but 30 which is, at the same time, adapted to operate the switch to which the lock is attached, and whereby the switch may be turned to battery, to magneto, or to neutral position by means of said key, and when in other 35 than neutral position the key can not be removed. By this construction I provide means whereby when the key is either fully or partly removed the switch must be in neutral, or off, position, and at such time 40 the lock will be in locked position, whereby the switch cannot possibly be otherwise operated.

My invention is particularly intended for 45 the dash-switch of automobiles or the like, for controlling the ignition system thereof, however it may be applied to electric lights or to other electrical equipment as desired, or for other purposes to which the principles thereof are adapted.

50 Other objects and particular advantages of this invention will be brought out in the course of the following specification.

The preferred means for carrying out the principles of my invention in a practical manner is shown in the accompanying drawings, in which—

Figure 1 is an interior plan view, taken from the rear, of the outer portion of the lock. Fig. 2 is an interior plan view, taken from the front, of the inner portion of the lock. Fig. 3 is a face elevation of the lock in position on the switch. Fig. 4 is an edge elevation of the relatively stationary parts shown in Fig. 2. Fig. 5 is a cross vertical section of the lock, showing the same in connection with the switch. Fig. 6 is a top plan view of the lock and a portion of the switch. Fig. 7 is a perspective view of the inner shell or sliding element. Fig. 8 is a perspective view of the core alone. Fig. 9 is an outside view of the central portion of the back plate of the lock. Fig. 10 is a face view of the central portion of the face of the switch. And Fig. 11 is a side elevation of the key alone.

75 Similar indices denote like parts throughout the several views.

In order that the construction, the operation, and the advantages of my invention may be more clearly understood and appreciated, I will now take up an exposition thereof, in which I will describe the invention as clearly and as comprehensively as I may.

In the drawings numeral 1 denotes the 85 front plate, and extending back from around the periphery thereof is the flange 2, which is at right-angles to the plate 1. Numeral 3 denotes the back plate, and it fits in the free edge of the flange 2. The said parts 90 form the case or shell of the lock. Formed in the edge of the plate 3, and spaced a short distance apart, are the two tongues 4 and 5, which are offset inwardly, and they are adapted to fit in the respective slots 6 and 95 7 which are formed near the edge of the flange 2, as shown in Fig. 6. A tongue 8 extends down from the plate 3, and a notch 9 is formed in the edge of the flange 2 in which said tongue is adapted to rest. The 100 tongue 8 is oppositely disposed from that of the center between the tongues 4 and 5, that is it is diametrically opposite thereto, as shown in Fig. 2.

Extending from the plate 1, parallel with the flange 2, and contacting with the inner face of the plate 3, are the posts 10 and 11. Opposite to said posts are apertures 12 and 13 formed through the plate 3, in which screws may be inserted, the same being threaded into the ends of the posts 10 and 11, respectively, whereby the plate 3 is secured in place in the case, in the position shown in Fig. 5, thereby retaining the members of the case in position.

Formed through the center of the plate 3 is the round aperture 14, and equally spaced therefrom, above and below, are the arcuate slots 15 and 16, which are concentric therewith.

In Fig. 8 is shown the rotatable core, comprising the disk 17, a central pintle 18, which extends from the center of one face 20 of the disk, the said pintle is adapted to fit the aperture 14. Also extending from the edge of said disk, and extending parallel with the pintle 18, are the two lugs 19 and 20, which are adapted to extend through the slots 15 and 16. From the opposite side 25 of the disk 17 extends the two lobes 21 and 22, which are spaced apart by the central slot 23. The disk 17 is adapted to rest on the plate 3 with the pintle 18 projecting through the aperture 14 and the lugs 19 and 20 projecting through the respective slots 15 and 16, and at the same time the free ends of the lobes 21 and 22 will contact with the plate 1.

35 The inner shell, shown in Fig. 7, comprises the ring or band 24, which fits snugly and slidably within the flange 2, resting on the plate 1 and located inward from the plate 3. Extending centerward a short distance from the interior of the band 24 is a flange 25 which is in sliding contact with the plate 1. A portion of the band 24 is reinforced or formed thicker than the remainder of the band, as indicated at 26. 40 Formed in the center of the reinforcement 26, and also the band 24, is the indent 27, and diametrically opposite thereto is the slot 28 which cuts the band 24 almost into two-parts, the same being at the center of 45 the flange 25. Formed through the flange 25 are two apertures 29 and 30 which may be brought into register with like apertures 31 and 32 of the plate 1.

Formed through the plate 3 are the apertures 33 and 34, and through the tongue 8 is the aperture 35, to receive the respective screws 36, 37 and 38, by which the lock is secured to the face of the switch 39. In the center of the face of the switch 39 is the 50 usual central fixed stem H, which has a central aperture I therein, and around the stem H is the rotatable shell J which has in its face the two notches K and L. Also corresponding notches M and N are formed in 55 vertical alinement with each other in the

face plate of the switch and which are adapted to register with the notches K and L when the shell is turned to a certain position, which heretofore has been accomplished by the usual switch key.

Secured to the plate 3 and extending to near the flange 25 and approaching near to the band 24, are the guards or guides 40 and 41, which are adapted to guide and position the screws 36 and 37.

Secured on the inner face of the plate 3, around the slots 15 and 16, is the hollow ellipsoidal plate 42, whose longer diameter is in alinement with the center of the tongue 8 and the notch 9. Also secured to the plate 3 80 and extending from one end of the plate 42 directly toward the notch 9, is the guide-block 43, which has at each corner an in-turned tooth, as the teeth a, b, c and d, thereby forming a guide-way between the teeth 85 at each end of the block. Located in alinement with the block 43 and projecting from the opposite end of the plate 42, and secured to the plate 3, is the smaller guide-block 44, which has no inwardly projecting teeth. 90

Near the tongue 8 an incision is made through the plate 3, and the material thereof is bent inward to form the hanger 45, and thereby forming the aperture 46 in the plate 3. Numeral 47 denotes a dog which is pivoted to the hanger 45 by means of the screw 48. The lip of said dog is normally located on or near to the face of the guide-block 44, as indicated in Fig. 4. Extending from the outer end of said dog is the tail 49 100 which is adapted to engage in the notch 27, or to ride on the edge of the band 24 and the reinforcement 26. The tail of said dog is normally retained in said notch 27 by the spring 50, the latter being secured to the 105 plate 3 as shown in Fig. 2.

Extending inward from around the sides of the plate 42, and connecting with the sides of the inner ends of the guide-blocks 43 and 44 are the flanges 51 and 52.

Numeral 53 denotes a two-way arcuate spring, the same having its center secured across and near the center of the block 43, with its ends deflected inwardly, for the purpose hereinafter mentioned.

Numerals 54 and 55 denote alining pins which are secured on the inner face of the plate 42 immediately at the inner ends of the respective blocks 43 and 44, and they extend inward to a level with the edges of the 120 flanges 51 and 52.

Formed circumferentially in the flange 2, centrally and parallel therewith, is the slot P, shown in Fig. 6. The center of said slot is in the center between the tongues 4 and 5, and it extends some distance, therebeyond as indicated. In the center of the slot P are the two oppositely disposed notches R and S, which are adapted to register with the slot 28, for the purpose hereinafter stated. 130

Turning now, more particularly, to Fig. 1, there is secured to the center of the inner face of the plate 1 an ellipsoidal plate 56, which corresponds in size and shape with the plate 42, and it is directed opposite thereto, and extending out from the ends of the plate 56 are the oppositely disposed guide-blocks 57 and 58, which are in alinement with each other and with the blocks 43 and 44 with 10 which they are oppositely disposed.

Extending inward from the two outer corners of the block 57 are the teeth *e* and *f*; and likewise extending inward from the inner corners of the block 58 are the teeth *g* and 15 *h*.

Extending inward from around the outer edges of the plate 56, and between the inner ends of the blocks 57 and 58, are the flanges 59 and 60, which are oppositely disposed to 20 and correspond with the flanges 51 and 52.

Numerals 61 and 62 denote alining pins secured on the inner face of the plate 56 immediately at the inner ends of the respective blocks 57 and 58, and they extend inward to 25 a level with the edges of the flanges 59 and 60, and they are located directly opposite to the alining pins 54 and 55.

Numeral 63 denotes the blade or body of the key, the same having in its outer edge 30 the indents or notches *u*, *v* and *w*, and in its inner edge are the notches *x*, *y* and *z*.

For the purpose of a clearer comprehension of the invention we will assume the removable parts to be dismantled, and will 35 proceed to place them in operative position, and will describe the operation thereof:

The switch 39 is assumed to be wired up in connection with the ignition system, in which it would stand vertical as in Fig. 5, 40 the face thereof appearing as in Fig. 10, the usual switch-key having been removed. This switch has three definite positions: "on battery," "on magneto" and "neutral" or "off" position.

45 Before attaching it to the switch the lock is to be assembled, first by placing the inner-shell, shown in Fig. 7, in its place as in Fig. 1, with the notch 27 central of the notch 9, which will bring the notch 28 in register 50 with the notches *R* and *S*. The core, shown in Fig. 8, is then placed on the inner face of the plate 1, as indicated by dotted lines in Fig. 1.

I next take the plate 3, with the parts 55 attached, as in Fig. 2, and after turning it over, to the right or the left, I bring it to the flange 2, first entering the tongues 4 and 5 in the slots 6 and 7, and then bringing the tongue 8 into the notch 9. The above operations will bring the tail 49 in the notch 27, and will project the pintle 18 through the aperture 14, and will project the lugs 19 and 20 through the slots 15 and 16. I next insert screws through the holes 12 and 60 13 and tighten them down into the posts 10

and 11, which manifestly secures the various parts of the lock in operative position.

After the above operations the lock will be found to be in locked position, and it could not even be attached to the switch 70 without first being unlocked.

To unlock, the operation is as follows: The key is inserted as shown in Fig. 5, that

is the point is entered through the slot 28, with its edges in the notches *R* and *S*, and

as it is pushed in it slides between the teeth *a* and *b*, and *e* and *f*, and then between the teeth *c* and *d*, then through the slot 23 of

the core, and then between the teeth *g* and *h*, finally engaging the lip of the dog and turning

the dog upon its pivot to the position in

which the dog is shown in Fig. 5, thereby moving the tail 49 out of the notch 27.

Simultaneous with the last mentioned operation the notches *x* and *v* will be in alinement

to receive the edge 24—26 of the case, thereby permitting the handle 64 of the

key to be moved to the right or the left, permitting the teeth *a* and *b* to pass through

the notch *y*; the teeth *e* and *f*, passing

through the notch *v*; the teeth *c* and *d* passing

through the notch *z*; and the teeth *g* and *h* passing through the notch *w*. At this

time the tail 49 will ride on the edge of the band 24, the inner shell of course turning

with the key. Moving the key to the right or the left will of course turn the core, thereby causing the lugs 19 and 20 to turn

the switch in the same manner as would the ordinary switch-key.

It will be observed that sliding the key a

short distance in one direction will cause the holes 29 and 30, of the flange 25, to

register at one point with the holes 31 and

32 in the plate 1, thereby permitting the

screws 36 and 37 to be inserted through the

holes 31—29 and 32—30, respectively, passing

down through the respective guards 40

and 41, and then by means of a screw-driver

the said screws may be inserted into the

threaded sockets therefor in the face of the

switch, as in Fig. 6. The screw 38 should

also be inserted through the tongue 8, then

into a socket therefor in the switch thereby

securing the lock to the switch.

It is evident that when the lock is in

locked condition the flange 25 will close

the holes 31 and 32, thereby preventing ac-

cess to said screws 36 and 37, and prevent-

ing the lock from being removed without

the employment of the key provided there-

for.

It is also evident that after the key has

been inserted it may be moved sidewise to

its limit at one end of the slot *P*, which

will cause the core to turn the switch "on

battery", while if it is turned to the limit

of the slot *P* in the opposite direction it will

turn the switch to "on magneto", in each of

which positions the spring 53 will press

the tongue 8 against the pintle 18, thereby

upon the key and prevent it from rattling, and also will hold the key from sliding out of position.

It will also be observed that the key can 5 not be removed so long as it is turned to the right or the left from the notches R and S, that is not until the switch is turned to neutral or "off" position, at which latter point the key may be removed.

10 It should be observed that when the key is brought to the notches R and S that this will bring the tail 49 of the dog in register with the notch 27, and that the first movement of the key outward will allow the 15 spring 50 to press the tail 49 into the notch 27 and thereby locking the device against inadvertent displacement.

It is now evident that after the key is removed that no access can be had to the 20 core, and therefore the switch could not be turned by anyone without the particular key for the lock.

By simply changing certain of the various teeth a, b, c, d, e, f, g, and h, radially, 25 or by changing the size of said teeth, or by omitting certain teeth or by adding others, and then by changing the notches in the key to correspond therewith, it is evident that innumerable combinations may be arranged, 30 whereby only a particular key will operate that particular lock for which it is intended.

I desire that it be understood that various changes may be made in the several details of construction, and in the arrangement and the shape of the various parts, 35 without departing from the spirit of my invention and without sacrificing any of the advantages thereof.

Having now fully shown and described 40 my invention, what I claim, and desire to secure by Letters Patent of the United States, is,—

1. In combination with an electric switch, a lock connected to the face of the switch 45 in such manner that it can not be removed therefrom except when the lock is in unlocked condition; a key for operating said lock, and means whereby the key can not be removed from the lock when the lock is in 50 unlocked condition.

2. In combination with an electric switch having two contact points and a neutral or off position midway said points, a lock secured to the face of the switch and affording the only means for operating the switch, 55 a removable key for operating the lock and for turning the switch to either point of contact or to neutral position, means whereby the lock can not be operated when the key is removed, and means whereby the key 60 can not be inserted or removed except when the switch is in neutral position.

3. In combination with an electric switch, a lock connected to the face of the switch 65 and including a central core adapted when

rotated to operate the switch, a dog for securing the lock in its locked condition, a key adapted to be inserted in the lock and to release said dog after which the key may be moved to the right or the left to rotate 70 said core, guide-ways for said key, teeth carried by the guide-ways, there being notches in the key to register with said teeth whereby when the key is inserted it may be moved sidewise, and also the key being 75 adapted to be inserted and removed only when said dog is in position to lock the device from the sidewise movements of the key, all substantially as set forth.

4. A switch lock comprising a case, a shell 80 slidable within the case, a core rotatable in the center of the case and having lugs extending through the case to engage a switch, a dog adapted to lock said shell from movements within the case, a key adapted to be 85 inserted at one point in the case whereby it will extend through said core and engage said dog to place the dog out of securing position, being adapted to be moved sidewise only when the dog is out of securing 90 position, and teeth located in the case for preventing the sidewise movement of the key except when said teeth register with notches therefor in the key and when said dog is out of its securing position. 95

5. A switch lock adapted to be secured to the face of a switch and having connection with the rotary part thereof, means whereby the device is in locked condition only when the switch is in off or neutral position, means whereby the lateral movements of the key after being inserted in the lock will operate the switch to "on" and "off" positions, the key being adapted to be removed only when the switch is in neutral 100 position.

6. A lock adapted to be secured to the face of a switch, and comprising a case having apertures in its back to register with the key apertures in the switch, a rotatable core 110 located in the center of said case and having lugs extending through said apertures in the case and fitting said apertures in the switch, an inner shell fitting and adapted to slide around in said case, there being a circumferential slot in the edge of the case 115 which is closed by said inner shell, there also being a key slot in the shell adapted to be exposed through said slot in the edge of the case, guide blocks secured in the case and located in alinement with said slot in the shell and with the center of the slot in the case, teeth projecting inward from said guide-blocks, a dog pivoted at the opposite end of said guide-blocks from said slots, a tail carried by said dog which tail normally presses into engagement with a notch in said shell, a key adapted to be inserted through said slot in the shell when the slot in the shell is at the center of the slot in 120 125 130

the case, the key when inserted being adapted to turn said dog and remove the tail thereof from the notch in the shell, the key when inserted being obliged to pass through a slot in the core, there being notches in the key to receive said teeth carried by the guide-blocks whereby the key after being fully inserted may be moved to the right or the left in the case with the center of said 10 core as the axis of its movements, all sub-

stantially as shown and described and for the purposes set forth.

In testimony whereof I have hereunto subscribed my name to this specification in the presence of two subscribing witnesses. 15
